E. E. HARDY,
ROLLER SKATE.
APPLICATION FILED AUG. 9, 1920.

1,406,644.

Patented Feb. 14, 1922.

Emery Eastman Hardy, Inventor
By Louis M. Schmidt, attorney.

UNITED STATES PATENT OFFICE.

EMERY EASTMAN HARDY, OF BROOKLYN, NEW YORK.

ROLLER SKATE.

1,406,644.

Specification of Letters Patent. Patented Feb. 14, 1922.

Original application filed January 15, 1920, Serial No. 351,579. Divided and this application filed August 9, 1920. Serial No. 402,368.

To all whom it may concern:

Be it known that I, EMERY EASTMAN HARDY, a citizen of the United States, residing at Brooklyn, in the county of Kings and 5 State of New York, have invented certain new and useful Improvements in Roller Skates, of which the following is a specification.

My invention relates to improvements in 10 roller skates, having relation to the form shown and described in certain patents already issued to me, to wit:—Nos. 1,152,813; 1,228,111; 1,276,212; and 1,345,848; and also in certain applications filed by me, to wit:— 15 Serial Nos. 351,579; 351,580 and 402,367; and is divisional of the application 351,579 mentioned and filed January 15, 1920, and the object of the particular improvement herein shown and described is to effect improved forms of construction and arrangement pertaining to the details of the hub structures and wheel mountings.

In the accompanying drawing:—

Figure 1 is a side elevation of my improved roller skate.

Figure 2 is a sectional view through the front wheel shaft, being on an enlarged scale.

Figure 3 is a sectional view through the rear wheel shaft.

Figure 4 is a view generally similar to Fig. 3, showing the two rear shaft members tilted from the normal position of alignment shown in Fig. 3.

Figure 5 is a sectional view through the pivotal connection for the two rear shaft members shown in Fig. 3, being on a still further enlarged scale.

Figure 6 is a fragmentary sectional view 40 corresponding to Fig. 3, and on a further enlarged scale, showing the hub portion of one of the rear wheels and connected parts removed from the shaft.

Figure 7 is a side elevation of the assembling sleeve for the wheel structure shown in Fig. 6 previous to having the ends turned up for holding.

My improved roller skate comprises a frame that is made of sheet metal and is 50 composed of a front frame member 10 and a rear frame member 11 that are separably and adjustably connected together; a shaft 12 connected to the front frame member 10

having mounted on the middle portion a front wheel structure 13; a shaft structure 55 that is composed of two component members 14 in alignment connected to the rear frame member 11 that supports by its ends the rear wheels 15; a heel stop member 16 at the front end of the heel space on the rear 60 frame member 11; and metal toe clamping members 17 operatively connected to the front frame member 10; and also, as regards the straps, has a novel arrangement for the toe straps 18 and also for the heel 65 straps 19.

The front frame member 10 has a pair of downwardly directed side arms 20 that are positioned in parallelism and are provided with suitable holes 21 for admitting the 70 front shaft 12.

The clamping screw 22 holds the toe clamping members 17 in place.

The rear frame member 11 has a pair of downwardly extended arms 23 that are positioned in parallelism and are provided each with a hole 24 of square form admitting a square portion 25 of one of the rear shaft members 14 and has a pair of upstanding rear heel lugs 26 that are suitably slotted 80 for receiving the heel strap 19.

Consideration will now be given to the wheel and axle construction.

The shaft 12 is entered through the holes 21 in the side arms 20 and is of substantially 85 stud form, comprising a cylindrical body portion at the middle with threaded end portions 27 and a nut 28 is mounted on the said threaded portion 27 that engages with the outer face of the side arms 20. Also, 90 there may be a cotter pin 29 on the end portion outside the said nut 28.

Between the arms 20 and mounted on the shaft 12 there is a sleeve 30 extending along the middle and major portion of the length 95 thereof, there may be a washer 31 opposed to the inner face of each of the arms 20, as shown, and intermediate the said washer 31 and the opposed end of the sleeve 30 is a washer 32 that serves as the outer cone bearing member for operatively housing the balls 33 of the ball bearing device at each end of the wheel structure 13.

The end portions of the sleeve 30 serve as the fixed cylindrical parts of the bearings 105 for the balls 33.

The parts are constructed and arranged so that the nuts 28 can be screwed on the shaft 12 tightly, so that the sleeve 30 and the cone members 32 at each end thereof serve as the fixed parts of the ball bearing construction.

The front wheel structure 13 is built up of two mating and similar members 34 that have their opposed edges 35 meeting along the medial line or plane, and have each on 10 the outer face a cup 36 for cooperating with the balls 33.

The cup 36 is provided in the form of a depression in a hub portion 37 and the cup 36 is made sufficiently deep to extend over 15 the periphery of the cone washer 32 and is an operative fit for the said periphery, suitably to serve as an emergency bearing on the outer side of the balls 33. Also, on the inner side of the balls 33 the opening 38 in 20 the hub portion 37 is an operative fit for the opposed portion of the sleeve 30.

The washer 31 is made to serve as a thrust bearing by being made sufficiently large, as shown, to extend beyond the opposed outer 25 face of the cone washer 32 so as to be adapted to engage with a part 39 of the opposed outer face of the wheel member 34.

Thus, as described, each individual wheel member or element 34 is adapted to operate 30 independently of the other, or to cooperate with the other mating member so that the two operate together, substantially as one wheel.

In the case of the rear wheel structure, 35 there is provided a rear wheel 15 on each side and the wheels are each individually mounted in a special manner so as to provide a complete and self-contained structure that is ready to be mounted in a relatively 40 simple manner on the outer end portion of the shaft member 14, such as shown, or of some other suitable form, the said structure comprising a complete bearing device for the wheel 15 that serves to operatively house 45 the said wheel and means for holding the parts together.

Referring to Fig. 6, the wheel 15 comprises a sheet metal structure having a generally inwardly directed hub portion 40 that is extended in sleeve-like form along the axis and has a bore 41 that fits over a sleeve 42. The outer end of the said bore 41 opens into an inwardly directed recess 43 of generally cup form. The inner portion 44 of the said recess 43 is rounded for cooperating as a raceway with the balls 45 of a ball bearing device and the outer portion 46 thereof is opposed to and fits over the periphery of a cone washer 47 that fits against 60 the end of the said sleeve 42.

The inner end portion 48 of the hub portion 40 is reduced for a short distance, terminating in a shoulder 49 so as to be a fit for and adapted to receive a cup structure 50

that serves as a finish for the inner end of 65 the hub portion 40 and also generally for the inner end portion of the wheel 15. Thus the said cup structure 50 serves essentially as a part of the wheel proper, and is rigidly connected to the main wheel element 15 so 70 as to rotate therewith, and has an opening 51 that fits over the sleeve 42.

The said opening 51 and the bore or opening 41 in the hub portion 40 are adapted to serve as an emergency bearing in cooperation 75 with the sleeve 42, that serves as a bearing sleeve, the said emergency bearing being on the inner side of the ball bearing involving the balls 45.

On the outer side of the balls 45 the outer 80 portion 46 of the cup 43 cooperates with the opposed periphery of the cone washer 47 as a bearing.

The inner face of the cup structure 50 is substantially flush with the adjacent inner 85 end of the bearing sleeve 42.

The cone washer 47 serves as the outer end of the fixed bearing structure and the inner end thereof is formed by a fixed or non-rotating structure 52 that is in the form of a 90 second and exterior cup structure that generally fits over the inner and rotating cup structure 50 and abuts against the end of the bearing sleeve 42.

The fixed cup structure 52 comprises the 95 body portion in the form of an annular wall that has a part of the inner face in abutment with the opposed inner end face of the bearing sleeve 42 and has a part opposed to the inner end face of the inner cup structure 100 50, and has the peripheral portion 53 in the form of a cylindrical extension that fits over and encloses the periphery of the inner cup structure 50, so that the two cup structures are adapted to cooperate as bearing devices. 105

The fixed bearing structure as described is composed of the bearing sleeve 42 at the middle, the outer cup structure 52 at the inner end thereof, and the cone washer 47 at the outer end thereof, and these parts are 110 fixedly connected in the following manner: The cup 52, sleeve 42, and cone 47 have openings that are of the same diameter and such as to fit over a cylindrical sleeve 54 of relatively thin sheet material, the body portion of which sleeve is of suitable length to extend through these parts, so that the end portions thereof may be headed or flanged 115 outwardly in some proper manner for rigidly holding the parts together.

As shown in Fig. 7, the said end portions 55 are provided with a plurality of slits 56 that extend inwardly from the ends so that each of the said end portions 55 is composed of a corresponding plurality of fingers 57 125 that are readily bent outwardly to form a head structure that is adapted to hold the parts together, as mentioned.

The holding sleeve 54 fits over the cylindrical part 58 of the shaft member 14. The extreme outer end portion 59 of the said shaft member 14 is, as shown, in the form of a head.

The two shaft members 14 are similar, positioned generally in alignment, and have the inner end portions 60 of semicircular form of cross-section, with the flattened parts 10 overlapping and pivotally connected together by means of a cotter-pin 61 that is positioned in holes that are provided in the overlapping portions, the cotter-pin 61 being generally directed horizontally. Thus 15 the two shaft members 14 may have a limited relative swinging movement, generally in a vertical plane.

The portions 62 of the shaft members 14 adjacent and outward from the overlapping flattened portions 60 may be of cylindrical form, and are reduced relatively to the outer cylindrical portion 58 that is housed in the holding sleeve 54. The square portion 25, already mentioned is positioned 25 intermediate these two cylindrical portions, which part is positioned in the hole 24 in the supporting arm 23 of the rear frame member 11, and is non-rotative therein, and is of such a fit therein as to permit of the 30 slight tilting movement of the wheels 15 relatively one to the other.

In assembling the parts the unit composed of the wheel and bearing structure therefor, held together as a unit by the holding sleeve 54, is mounted on the shaft member 14 and positioned on the outer cylindrical portion 58, with the holding sleeve 54 in abutment with the head 59, and then the reduced portion 62 is entered through the 40 hole 24 and the square bearing on supporting part 25 brought into position in the said hole 24.

The detail of operatively connecting the overlapping portions 60, involving the positioning of the cotter-pin 61, involves a housing structure 63 that fills the space between the two side supporting arms 23 and encloses or houses the overlapping parts 60 and all of the adjacent parts of the shaft members 50 14 that are positioned between the said side arms 23, and the said housing structure 63 is positioned by means of the cotter-pin 61, which extends entirely therethrough.

The said housing structure, furthermore, 55 serves as the means for limiting the relative tilting, swinging, or rocking movement of the shaft members 14 and for cushioning such movement, and does these in the following manner: The said structure comprises at the exterior a shell 64 in the form of a tube of appreciably greater diameter than that of the shaft members 14 housed therein and that is of suitable length to have the ends abut against the opposed

faces of the frame supporting arms 23 and 65 the entire interior space between the inner wall of the shell or tube 64 and the shaft members 14 is filled with a cushioning device 65 that is composed of relatively soft rubber.

Thus the rubber 65 is adapted to provide a yielding or resilient element in the means that serve to operatively connect the shaft members 14, such as to yield under appreciable pressure or force, so that these parts 75 are connected in a relatively flexible manner. By having the pivotal pin 61 positioned horizontally such yielding is mostly confined to movements in an approximately vertical plane.

I claim as my invention:—

1. In a roller skate, a wheel body formed of sheet material and having a hub portion that is provided with an inwardly directed cupped portion, a bearing sleeve for cooperating as a bearing device with the extreme inner and axial portion of the said hub portion and also with a set of balls at the inner portion of the said cupped portion, an annular cone member for closing the said 90 cupped portion, positioned in abutment with the outer end portion of the said sleeve, and having the periphery housed within the opposed border wall of the said cupped portion, and means for holding the said 95 cone member in position at the said outer end portion of the said sleeve.

2. In a roller skate, a wheel structure having a cupped portion opening inwardly from one face, the end wall of the said 100 cupped portion having an opening that is adapted to receive a bearing sleeve, the outer portion of the enclosing wall of the said cupped portion being adapted to cooperate with the peripheral portion of an annular cone member positioned at the outer end of the said sleeve, and the inner part 105 of the said cupped portion being adapted to serve as a raceway for a set of bearing balls.

3. In a roller skate, a wheel structure as described in claim 2, and an inner cupped structure serving as an extension and finish to the said structure on the side remote from the said cupped portion and also having an opening that is adapted to receive the said bearing sleeve.

4. In a roller skate as described in claim 3, an exterior cupped structure for operatively housing the said inner cupped structure and fitting against the inner end of the said bearing sleeve, and a holding sleeve having the body portion extended successively through the outer cupped structure, through the bearing sleeve, and through 120 the cone member, and having the end portion flanged outwardly to serve as holding heads for holding the parts together.

5. In a roller skate, a bearing shaft of tubular form, a washer-like structure for limiting endwise movement of the wheel positioned in abutment, one at each end 5 of the said bearing shaft, a wheel structure operatively mounted on the said bearing shaft and positioned between the said washer-like structures, and a holding tube entered through the openings in the said shaft and washer-like structures and having 10 flanged end portions in abutment with the outer faces of the said washer-like structures for holding the parts together.

EMERY EASTMAN HARDY.
